UNITED STATES PATENT OFFICE.

EDWARD J. SCHREMP, OF UTICA, NEW YORK.

METHOD OF CUTTING AND MAKING UNDERWEAR.

1,211,766.

Specification of Letters Patent.

Patented Jan. 9, 1917.

Application filed March 1, 1912. Serial No. 680,829.

To all whom it may concern:

Be it known that I, EDWARD J. SCHREMP, a citizen of the United States, residing at Utica, in the county of Oneida and State of New York, have invented new and useful Improvements in Methods of Cutting and Making Underwear, of which the following is a specification.

This invention relates to underwear and 10 more particularly to that type of garments known in the art as bifurcated nether and union garments and the invention resides specifically in the method of cutting the garments out of tubular knit fabric without 15 waste, each portion severed from the tubular strip being utilized in the composition or make up of the garment.

Further objects of this invention will appear as the following specific description is 20 read in connection with the accompanying drawing, which forms a part of this application, and in which:—

Figure 1 is a plan view of a tubular piece of fabric showing the line of cut to be made 25 so as to produce both legs and waist of the garment. Fig. 2 is a plan view of one of the parts unfolded. Fig. 3 is a plan view of a tubular piece of fabric showing the line of cut to obtain the seat gusset. Fig. 4 is a 30 plan of one of the seat gussets unfolded. Fig. 5 is a front elevation of the completed drawers. Fig. 6 is a rear elevation thereof.

Referring to the drawings 1, represents a tubular piece of fabric which is cut through 35 both folds upon the line 2 to produce the leg portion, as shown at 3 in Fig. 2. Both of the leg portions produced are sewed together to a point approximately indicated by the letter X, which point would be arranged 40 when the garment is being worn at approximately the knee of the wearer or slightly above. The crotch and seat piece or gusset is formed by cutting through the tubular piece of fabric shown at 4 upon the line 5 45 and then slitting each gusset piece longitudinally from the point 6 to the point 7 and then cutting diagonally across upon the line 8 to produce the crotch piece 9. This seat and crotch gusset is stitched into place, the 50 tapered projections 10 thereof having their side edges stitched to the side edges of the leg pieces 3 so as to increase the diameter of the legs at the thighs and across the buttocks. The crotch piece is carried up be- 55 tween the legs, as shown, and stitched in the

usual manner. A suitable reinforcing piece 11 is applied which reinforces the fly and forms a waist band for the garment and at the edges of the fly there are provided suitable securing means as the buttons and button holes indicated, such construction being of the ordinary type. It will be noticed that the entire garment, with the exception of the reinforcement 11, is constructed from tubular knit fabric without the slightest particle of waste in the cutting and that a seamless seat garment is produced. Not only is this feature observed, but all of the seams in the garment are on the bias, and thereby free from ripping.

What is claimed is:—

1. The method of forming bifurcated undergarments from tubular knit fabric which consists in severing a portion of the tube by an irregular longitudinal cut through both folds simultaneously to form enlarged and diminished portions of oppositely arranged legs, severing through both folds of another portion of the tube to form counterpart gusset pieces, slitting the gusset-pieces so formed centrally to divide the lower portion thereof into depending tapering leg gussets, severing the gusset by short slits diverging from the upper extremity of the central slit to provide a triangular crotch 85 gusset, sewing together the edges of the leg portions at their bottom ends, sewing the upper edges of each leg portion to the edges of the leg gussets to form enlarged thigh portions, sewing the upper portions of each leg section to the upper edges of the gusset piece to close the rear body portion, seaming the edges of the triangular gusset piece to the lower front edges of the body portion to form a crotch portion and providing securing means to close the front body opening of the garment when worn.

2. The method of cutting bifurcated undergarments from tubular knit fabric which consists in severing a portion of the tube by an irregular longitudinal cut through both folds simultaneously to form enlarged and diminished portions of oppositely arranged legs, severing through both folds of another portion of fabric to form counterpart gusset pieces, severing the gusset pieces to provide opposite leg gussets tapering toward their lower ends and to form a centrally arranged triangular crotch gusset, sewing together the edges of the leg portions at their bottom 105 110

ends, sewing the upper edges of each leg portion to the edges of the leg gussets to form enlarged thigh portions, sewing the upper portions of each leg section to the upper edges of the gusset piece to close the rear body portion, seaming the edges of the triangular gusset piece to the lower front edges of the body portion to form a crotch portion and providing securing means to

close the front body opening of the garment 10 when worn.

In testimony whereof I affix my signature in presence of two witnesses.

EDWARD J. SCHREMP.
